No. 643,963.

Patented Feb. 20, 1900.

A. HUBER.

STREET RAILWAY SWITCH OPERATING DEVICE.

(Application filed Dec. 8, 1899.)

(No Model.)

UNITED STATES PATENT OFFICE.

ADOLF HUBER, OF ST. LOUIS, MISSOURI.

STREET-RAILWAY-SWITCH-OPERATING DEVICE.

SPECIFICATION forming part of Letters Patent No. 643,963, dated February 20, 1900.

Application filed December 8, 1899. Serial No. 739,707. (No model.)

To all whom it may concern:

Be it known that I, ADOLF HUBER, a citizen of the United States, residing at 2243 Shenandoah avenue, in the city of St. Louis and State of Missouri, have invented a new and useful Street-Railway-Switch-Operating Device, of which the following is a specification.

My invention relates to improvements in railway - switch - operating devices in which between two longitudinal rails, with a plate-rail on top in the midway of the main track, vertically-reciprocating and simultaneously-moving levers operate, in conjunction with a switch-tongue, a mechanism attached to the platform of a car for the operating purpose; and the objects of my improvements are, first, to provide a regulating apparatus to open or close a switch for either side of the track; second, to afford facilities in putting a switch in any desired position from a platform of a car while the latter is in motion, and, third, to avoid obstructive mechanism above the surface of the street. I attain these objects by the mechanism illustrated in the accompanying drawings, in which—

Figure 1 is a vertical side view of the mechanism attached to the platform of a car, showing the combinations with the little wheels, one in a inoperative and the other in an operative position; Fig. 2, a top view of the switch and the regulating apparatus as they appear after the removal of the plate-rail; Fig. 3, a side view of the vertical section of a part of the regulating apparatus as it appears after the removal of one rail; Fig. 4, a top view of a section of a part of the plate-rail, showing the surface of the extending part of the levers between the grooves; Fig. 5, a vertical front view of the mechanism attached to the platform of a car, showing the combinations with the little wheels, one in an operative and one in an inoperative position; Fig. 6, a front view of the regulating apparatus in connection with the switch-tongue; Fig. 7, a side view of a vertical section of a switch-tongue and its connection with the rod.

Similar numerals refer to similar parts throughout the several views.

The longitudinal rails 17 and 18, its plate-rail 11, secured to the top of said rails 17

and 18, the short rails 22, 23, and 24, and its plate or cover 20 on top, constitute the inclosure of the regulating apparatus. In the rails 17 and 18 partially rotates a shaft 4, carrying a three-armed rocker-lever 3, having at its two upper arms a connection with the links 5 and 6, and to the latter are pivoted the bars 7 and 8, which are resting at their forward ends on the pins 9 and 10, and said pins 9 and 10 are secured to the said rails 17 and 18, horizontally extending inwardly from each side of said rails 17 and 18 and passing through an opening in the said levers 1 and 2 without being in contact therewith when moved down or upward, and said pins 9 and 10 also pass through an opening at the forward ends of said bars 7 and 8, holding either of said ends in an upward position when either of the rearward ends are moved downward (see Fig. 3) rearwardly from the front of said bars 7 and 8. Adjacent to the levers 1 and 2 are connections 25 and 26, and said levers 1 and 2 are pivoted at the rearward end to the said rails 17 and 18, and part of the latter toward the front vertically extend and pass through an opening in the said plate-rail 11 internally of the grooves 27 and 28, having the rearward end of the extension when in its inoperative position even with the bottom of said grooves and rising toward the front end even with the surface of said plate-rail 11, so that gradually the depressing of either of the said levers 1 and 2 with either of the little wheels 31 or 32, attached to the platform of a car, may be accompanied with as little force as possible.

The three-armed rocker-lever 3, previously referred to and shown in Fig. 3, with its downward arm, is connected with rod 12, which is forwardly at a predetermined distance hooked in a bell-crank lever 13, and the latter is fulcrumed on a vertical axle 14, which is provided with a nut 16 on top and secured to a sleeper 71 with head-screws 15 15. Said lever 13 is connected by a rod 19 to a bar 21, and the latter is secured to a switch-tongue 95 with a pin 30, as shown in Fig. 6.

The hangers 46, 47, and 48 and the two hanging rods 35 and 36, in connection with a forked bar 41, secured at its upper end to the hanger 46 and at its two lower ends to the 100

said hanging rods 35 and 36, constitute the framework of the attachment to the platform of a car for the operating purpose. The said rods 35 and 36 hold a shaft 38, which is provided with a nut 37 on each end, carrying two arms 33 and 34, to which are attached the wheels 31 and 32. Said arms 33 and 34 are pivotally connected with the rods 39 and 40 and the latter to the upper arms 42 and 45, comprising two shafts 43 and 44, which are journaled in the two hangers 46 and 47. Inwardly of the said hanger 46 the said arm 42 is secured to the said shaft 43, and to the latter outside of the hanger 47 is secured the 15 arm 49, and said arms 42 and 49 are in direction to each other at a right angle, and the arm 50 is secured to the said shaft 44 inwardly of the said hanger 47, and the said arm 45 is secured to the said shaft 44 outside of 20 the said hanger 46, and said arms 45 and 50 are in direction to each other at a right angle. Forwardly the shaft 70 is held secure by the said hanger 48, and said shaft 70 is carrying the two bell-crank levers 53 and 54, 25 which are pivotally connected with the rods 51 and 52 and the latter with the said arms 49 and 50. The foot-posts 57 and 58 vertically pass through lugs 60, which are attached to the platform of a car, and said foot-posts 30 57 and 58 are pivotally connected by links 55 and 56 to the said bell-crank levers 53 and 54.

The suspension-springs 63 and 64 are hooked in at the front to eye-heads 61 and 62, which are fastened to the said rods 51 and 52, and 35 at the rearward ends said springs 63 and 64 are hooked in eyebolts 66, which are secured to the cross-piece 65.

The numerals 67, 68, and 69 are parts of a street-car and its platform, showing the adjustable attachment thereto. I prefer to carry out this feature of my invention in the manner shown in Figs. 1 and 3, where it will be seen that two foot-posts 57 and 58 rise vertically from the top of the platform of a car at 40 the most convenient place of the same to operate thereon. The foot-post 58, in connection with the little wheel 32, is adapted to open a switch on either side of the track, and the foot-post 57, in connection with the little 45 wheel 31, is adapted to close it on either side of the track. The suspension-springs 63 and 64 automatically bring the little wheels when operative back to their inoperative position. The said levers 1 and 2, with their slight extension between the grooves 27 and 28 and 50 their connection with the said bars 7 and 8, the links 5 and 6 and the said three-armed rocker-lever 3. Either one of the said levers 1 and 2 when depressed causes the said lever 55 3 at its depressing-arm to go down farther and those moving the said rod 12, in connection with a switch, forward or backward, corresponding to the respective space required for a switch to bring it from one side to the 60 other. Depressing one of the said levers 1 and 2 causes the other simultaneously to come up,

so, therefore, this regulating apparatus being always ready for operating a switch in any position, right or left, closed or open.

Having described my invention, what I claim as new, and desire to secure by Letters Patent, is—

1. The combination, in a switch-operating device, comprising two longitudinal rails 17 and 18 with a plate-rail 11 secured on top, having two grooves on said plate-rail, levers 1 and 2 partially extending internally therein, means connected with a platform of a car for operating said levers, a shaft 4 journaled between said rails 17 and 18 carrying a three-armed rocker-lever 3 of which the two upper arms being pivotally connected with the said levers 1 and 2, by the adjacent bars 7 and 8, and the links 5 and 6, the said bars 7 and 8 rest at the forward end on pins 9 and 10 and 85 said levers 1 and 2 being pivoted at the rearward end inward of said rails 17 and 18, a rod 12 hooked in at its rear end to the downward arm of the said three-armed rocker-lever 3 and at its front end to the bell-crank lever 13, 90 which being fulcrumed on a vertical axle 14, and said lever 13 being pivotally connected with the switch-tongue by a rod 19 and a bar 21, all substantially as set forth.

2. In a switch-operating device, the combination comprising two longitudinal rails 17 and 18 with a plate-rail 11 secured on top, having two grooves on said plate-rail, two vertically-reciprocating and simultaneously moving levers 1 and 2, partially extending through the said grooves; having two independent combinations for operating the two said levers, of which each being provided with a foot-post extending on the top of a platform of a car, a connection with a bell-crank lever by a link and said bell-crank lever being pivoted to a rod, which being attached to an arm secured to a shaft and on the other end of said shaft being secured to an arm at a right angle; and said arm having a pivotal connection with a downward-hanging rod, which being pivoted at its lower end to an arm mounted at its forward end on the shaft 38 and at its other end being provided with a little wheel, which when in an operative position, passes through the said groove and depressing the extension of said lever causing the switch to change, substantially as described.

3. In a switch-operating device, an attachment to a platform of a car for operating purpose on the mechanism in the midway of the main track, two independent combinations with its little wheels adapted, one to open a switch on either side of the track and the other to close it, said combinations are held in position by the hangers 46 and 47, and the forward hanger 48 holding the shaft 70, two hanging rods 35 and 36 holding the shaft 38, in connection with a forked bar 41 which is secured at its upper end to the said hanger 46 and the two said hangers 46 and 47 hold-

ing the shafts 43 and 44, two suspension-springs secured to the rods 51 and 52 and to a cross-piece below the platform, automatically bring the operative little wheel back to 5 its inoperative position, substantially as shown, for the purpose specified.

In testimony whereof I have signed my

name to this specification in the presence of two subscribing witnesses.

ADOLF HUBER.
